(57) **CLAIM**

The ornamental design for a concealment cap for cable tensioning mechanism, as shown and described.

DESCRIPTION

FIG. 1 is a perspective view of the concealment cap for cable tensioning mechanism used with a horizontal support member;

FIG. 2 is a perspective view thereof, in an alternate condition of use;

FIG. 3 is another perspective view thereof, used with a vertical support member;

FIG. 4 is an enlarged exploded perspective view thereof, used with a horizontal support member;

FIG. 5 is an assembled perspective view thereof;

FIG. 6 is a perspective view of the threaded portion of the the concealment cap for cable tensioning mechanism shown separated for ease of viewing;

FIG. 7 is a side view thereof; and,

FIG. 8 is a front view thereof.

The concealment cap for cable tensioning mechanism is for concealing a tensioning mechanism situated inside a vertical or horizontal support member of a cable railing system. The broken lines in the drawings are for the purpose of illustrating the environment and form no part of the claimed design.
